PASCAL P. CHILD, OF ST. LOUIS, MISSOURI, ASSIGNOR TO S. R. FOX
MANUFACTURING COMPANY, OF SAME PLACE.

Letters Patent No. 72,603, dated December 24, 1867.

IMPROVEMENT IN HINGES FOR WINDOW-SHUTTERS.

The Schedule referred to in these Letters Patent and making part of the same.

TO ALL WHOM IT MAY CONCERN:

Be it known that I, PASCAL P. CHILD, of St. Louis, in the county of St. Louis, and State of Missouri, have made certain new and useful Improvements in Blind-Hinges; and I do hereby declare that the following is a full and clear description thereof, reference being had to the accompanying drawings, and to the letters of reference marked thereon:

This invention relates to an improvement upon the Lull & Porter hinge, patented January 31, 1854. The central spindle, cam-arms, and inclined planes used in the hinge above referred to, are also used in this hinge. The chief features of the improvement consist of an eccentric flange surrounding the central pivot or spindle, and a projecting lip on the other part of the hinge that overlaps the said eccentric flange when the two parts are together, and prevents the blind or shutter from being thrown from its hinges, except at one small point, thus obviating the difficulty of having the blinds blown off when opened.

To enable those skilled in the art to make and use my improved hinges, I will proceed to describe their construction and operation.

Figure 1 of the drawings is a perspective view of a pair of the hinges removed from the shutter, but coupled together as they would appear when in use.

Figure 2 is an elevation of the two parts of the hinge detached from each other.

Figure 3 is a plan of the two parts of the hinge detached, as in fig. 2.

This hinge, like that of Lull & Porter, above referred to, is a self-locking hinge, cast in two pieces, A and B, which are pivoted together by means of a central spindle, C. This hinge is also like the Lull & Porter hinge, in that it has cam-arms, *a* and *b*, which are provided with inclined planes, which allow the shutter-hinge to rise up on the stationary hinge in swinging to, until a certain point is attained, when sectional collars receive the weight and sustain it until the shutter is closed. When swung open, the cam-arms drop behind each other, just before the blind is open, and hold it there in a fixed position against the wall of the building.

From the foregoing description of the Lull & Porter hinge, it is evident that when the blind or shutter was at any point outside of the rebating of the window-frame, it might easily be lifted off its hinges, even by a gust of wind, and it was peculiarly liable to such a mishap when a person attempted to pull the shutter to or close it, as, to do so, it would be necessary to slightly raise the shutter in order to allow the cams to rise over their corresponding inclined planes.

It is to overcome this difficulty that the present invention is devised, and it is accomplished in the following manner, to wit: The upper part of the leaf of the hinge A is, in this instance, provided with a lip or wing, A', that extends over toward the spindle C, just as far as it is possible to do and leave room for the socket of the hinge B to slip on to the said spindle when the two wings of the hinge are placed perpendicular to each other. The upper part of the cam *b* is also widened out into an eccentric flange, *b'*, which is shown best in fig. 3. This flange can only pass below the point of the lip or wing A' at *x*, which point is directly in the central front part of the said flange, which, from that point, is widened out by the addition of that metal which is added outside of the dotted line *x'* in fig. 3, the distance between the said dotted line and the periphery of the flange being about one-sixteenth to one-eighth of an inch behind the hinge.

From this description it is evident the hinges must be turned so that the point of A' will pass below the flange *b'* at *x*, when the hinges are to be coupled, and that at no other point can the hinge B and its shutter be blown or lifted off from the spindle C, when the hinges are in use.

The hinge B might, of course, be constructed with a projecting lip in the place of the lip A', which, in that case, would lock under the cam *a*. This construction would evidently be a full equivalent for the other device.

Having described my invention, what I claim, is—

The lip A' upon either half of the hinge A B, projecting over or under the flange *b'*, as the case may be, in such manner as to come in contact with and act as a stop for the flange *b'* when the blind is inadvertently raised, as shown and described.

PASCAL P. CHILD.
